[57] ABSTRACT

A semiconductor integrated circuit is formed on a semiconductor substrate and includes a current mode type logic circuit and a constant current circuit to supply a constant current to the logic circuit. A reference resistor for adjusting the constant current is provided separately from the semiconductor substrate and connected to the constant current circuit. With this construction, fluctuations of the amplitude of the logic circuit output signal may be reduced.

SEMICONDUCTOR INTEGRATED CIRCUIT

BACKGROUND OF THE INVENTION

This invention relates to semiconductor integrated circuits, and more particularly, to improvements in current mode type semiconductor integrated logic circuits used in digital computers and the like.

DESCRIPTION OF THE PRIOR ART

Current mode type logic circuits have heretofore been used as the highest speed logic circuit in digital computers and the like. One of the most important problems encountered when integrating such logic circuits is how to reduce fluctuations in the output signal amplitude. If emitter resistors and collector load resistors of a logic circuit are integrated in the same semiconductor, it is possible to obtain an output voltage with high precision. However, if the collector load resistors are provided separately from the integrated circuit, it is not possible to obtain the output voltage with high precision, and wide fluctuations in the output are inevitable.

In large size computer systems, numerous circuit elements are employed, so that their mounting structure requires a considerably large amount of space. By way of example, in such a system, the output of one logic circuit often has to be transmitted over a transmission line as long as several tens of centimeters to several meters.

As is well known in the art, to reduce reflections in the transmission line, it is effective to provide a distributed constant line having comparatively uniform characteristic impedance for the transmission line and terminate the reception end of the line with a resistance substantially equal to the aforementioned characteristic impedance.

In this case, however, the transmission line and terminal resistor are provided externally of the integrated circuit, so that the output voltage is subjected to wide fluctuations. Therefore, even if the afore-mentioned logic circuit is integrated, the integrated circuit can never be expected to be practically employed in digital computers.

An object of the invention is to provide a semiconductor integrated logic circuit, in which the fluctuation of the output signal amplitude can be made very small, even if collector load resistors are externally provided.

Another object of the invention is to provide a semiconductor integrated logic circuit which is capable of driving an external transmission line.

A further object of the invention is to provide a semiconductor integrated logic circuit which enables driving long transmission lines in digital computers and the like without any provision of various conversion circuits.

In accordance with the invention, the above various objects are achieved by integrating one or more current mode type logic circuits on a semiconductor substrate together with a constant current circuit connected to the logic circuit or circuits and providing an outer reference current source or reference resistor external to the integrated circuit for specifying the output current of the constant current circuit, thereby enabling the output of the logic circuit or circuits to be coupled to an outer impedance such as transmission line.

BRIEF DESCRIPTION OF THE DRAWINGS

FIGS. 1a and 1b show an example of a prior-art current mode type logic circuit.

5 FIG. 2 is a schematic of the basic circuit according to the invention.

FIG. 3 to FIG. 6 are circuit diagrams of examples of the constant current circuit used in accordance with the invention.

10 FIGS. 7 to 11 are schematics showing preferred embodiments of the invention.

DESCRIPTION OF THE PREFERRED EMBODIMENTS:

15 FIGS. 1a and 1b illustrate an example of the prior-art current mode type logic circuit. The illustrated circuit includes input transistors T_1 and T_2 which have their emitters and collectors commonly connected and their bases connected to respective input terminals A and B, and a third transistor T_3 to the base of which a reference voltage V_{BB} is applied. In accordance with the relative amplitude of the input voltages impressed upon the input terminals A and B relative to the reference voltage V_{BB} , NOR and OR outputs may be obtained at respective output terminals O_1 and O_2 .

20 In this logic circuit, the amplitudes of the respective outputs are determined by the reference voltage V_{BB} and respective resistance ratios R_{CP}/R_{EE} and R_{CN}/R_{EE} of collector load resistances R_{CP} and R_{CN} to emitter load

25 resistance R_{EE} for the input transistors. Accordingly, in

30 integrating this logic circuit by forming the collector load resistors R_{CP} and R_{CN} and emitter load resistor R_{EE} in the same semiconductor substrate (indicated as a dashed rectangle) a comparatively superior precision,

35 for instance about $\pm 3\%$, may be obtained for the afore-

mentioned resistance ratios, so that fluctuations of the output signal amplitude, mentioned earlier, may be reduced.

40 However, if it is intended to drive a transmission line

1 which is external to the integrated circuit in place of the afore-mentioned collector load resistance, it is difficult to obtain a high precision for the resistance ratio between terminal resistance R_T which corresponds to the afore-mentioned collector resistance and the emitter load resistance, so that the signal amplitude will fluctuate to a great extent up to about $\pm 20\%$.

45 In accordance with the invention, the afore-mentioned logic circuit, which is generally designated at

50 3 in FIG. 2, is integrated on a semiconductor substrate 2 together with a constant current circuit 4 connected to the common emitter terminal of the logic circuit, and a reference resistor R_f for determining the output current I_{CS} is provided separately from the integrated circuit. With this arrangement, the current I_{CS} which is determined by the reference resistor R_f external to the integrated circuit is supplied to the logic circuit 2 and the fluctuation of the resistance ratio or current ratio within the integrated circuit can be reduced.

55 Thus, the dependance of the collector output current from the logic circuit 2 upon the resistors within the integrated circuit can be reduced. In this manner, fluctuations in the amplitude of the signal V_S appearing across the terminal resistor R_T when the external transmission line 1 is driven can be extremely reduced.

60 65 FIG. 3 shows an example of the constant current circuit. Referring to the figure, if transistors T_4 , T_5 and T_6

have an equal current amplification factor h_{FE} , the relation between driving current I_A flowing from terminal 5 and collector current I_{CS} in the transistor T_6 can be expressed as

$$I_{CS} = f h_{FE} 2 / (1 + r + h_{FE} 2) I_A \dots \quad (1)$$

where r is the emitter area ratio between the transistors T_4 and T_6 .

In equation (1) the value of $h_{FE} 2$ is very large compared to the value of $(1 + r)$ so that the latter can be ignored. Then,

$$I_{CS} = r I_A$$

which signifies that if the driving current I_A is constant, the collector current I_{CS} (output current) can be made constant.

When the above constant current circuit is used as a driving power source for the logic circuit 2 as mentioned earlier, the driving current I_A is determined by the source voltage V_{EE} , forward voltage V_{BE} across the base-to-emitter path of the transistors T_4 to T_6 and the resistance of the reference resistor R_f . Meanwhile, the collector current I_{CS} in the transistor T_6 is substantially proportional to the driving current I_A , as mentioned earlier. Thus, it will be apparent that by suitably selecting the source voltage V_{EE} and the resistance of the reference resistor R_f , a given constant current may be supplied to the logic circuit.

FIG. 4 shows another constant current circuit, which includes resistors R_4 and R_6 in series with the respective emitters of the transistors T_4 and T_6 and serving to determine the current ratio. If the resistance ratio R_4/R_6 is made equal to the afore-mentioned emitter area ratio r between the transistors T_4 and T_6 , the current ratio I_{CS}/I_A can be made to be still closer to r . If R_4/R_6 is not equal to r , the current ratio I_{CS}/I_A will usually not approximate but will rather be determined by R_4/R_6 .

If the resistance R_4 is sufficiently small, compared with the reference resistance R_f , the current is substantially determined solely by R_f , while with R_4 set to be equal to or nearly equal to R_f , the current I_A is determined by both the resistances R_f and R_4 . The latter arrangement is effective in a case as shown in FIG. 11 where part of the collector load of the logic circuit is constituted by resistor R_{CT} within the integrated circuit and the rest of the load is constituted by resistor R_T external to the integrated circuit. In this case the resistance R_4 within the integrated circuit and resistance R_{CT} provide a certain correlation and will vary always in the same direction, thus assisting the reduction of the fluctuation of the signal amplitude of the logic circuit output.

In the circuit of FIG. 5, where a series circuit of resistor R_1 and diode D_1 is connected in parallel with transistor T_4 , the variation in the collector current in the transistor T_4 can be compensated to some extent by the variation of the driving current I_A due to fluctuation of the afore-mentioned base-emitter forward voltage V_{BE} and temperature variations.

FIG. 6 shows still another constant current circuit. In this circuit, the collector potential on the transistor T_4 is compared with the reference voltage V_f by a differential amplifier constituted by transistors T_8 and T_9 and resistors R_9 and R_{10} , and the result is amplified and supplied to the common base terminal of the transistors T_4

and T_6 through an emitter follower circuit consisting of transistor T_5 and resistors R_2 and R_5 .

With this construction, with a decrease in the current I_A flowing through the resistor R_f , for instance, the collector potential of the transistor T_4 is increased to increase the base potential of the transistor T_5 , thus eventually increasing collector current in the transistor T_4 and hence the current I_A . Thus, the driving current I_A can be specified by the reference resistance R_f and reference voltage V_f . Again in this case, if the transistors T_4 and T_6 have an equal emitter area and the resistors R_4 and R_6 have an equal resistance, the collector currents in the transistors T_4 and T_6 may be maintained to be the same.

15 It will be noted that the reference resistor R_f in the preceding constant current circuits may be replaced with a reference current source independent of the integrated circuit.

FIG. 7 shows one embodiment of the invention. LSI₁ and LSI₂ designate semiconductor substrates in which a plurality of current mode type logic circuits are integrated. Logic circuits IG₁₁ to IG₂₂ drive transmission line 7 as an external load which is comparatively short so that no reflection problem is encountered. Accordingly, they are not constructed to be supplied with any constant current as mentioned above.

On the other hand, the outputs X₁, X₂ and X₃ of logic circuits EG₁₁ and EG₁₂ are coupled through a comparatively long external transmission line (not shown) to associated logic circuits in LSI₂. Similarly, the outputs of logic circuits EG₂₁ and EG₂₂ are coupled through a transmission line 6 to associated logic circuits in LSI₁. Terminal resistors R_7 of the transmission lines are grouped on printed circuit plates R_{TG1} and R_{TG2} . The resistor groups each include a surplus resistor used as reference resistor R_f for a corresponding one of the constant current circuits CS₁ and CS₂. The logic circuits EG₁₁ to EG₂₂ are constructed to be supplied with a constant current from the constant current circuits CS₁ to CS₂ since they each drive a comparatively long transmission line, as mentioned above.

40 If opposite ends of the transmission lines terminate in respective resistors R_T as shown in FIG. 8, the output current I_{CS} of the constant current circuit may be set to be double that in the case of a single end termination of a transmission line with resistance.

50 In the FIG. 9 embodiment, Schottky barrier diodes SBD₁ and SBD₂ are provided for clamping low level portions of the output signal. With this construction according to the invention, there is no need of causing the flow of extra gate current to ensure that clamping always takes place at a given low level, so that the power consumption may be reduced.

55 While the foregoing description of the invention has concerned with on-line current mode type semiconductor integrated logic circuits, similar effects as described above may also be obtained when the invention is applied to a so-called emitter-to-emitter coupling integrated logic circuit as shown in FIG. 10.

60 It is to be noted that any well known method may be employed to realize an integrated circuit according to the invention.

As has been described in the foregoing, according to the invention it is possible to drive transmission line which has been practically impossible with the usual collector drive type integrated circuit. Also, no particular conversion circuitry is required for the driving of

transmission lines. Further, the transmission output from one integrated logic circuit may be directly coupled to another, so that any conversion circuit in the path from transmission line to the inside of integrated logic circuit is not needed, which is extremely beneficial in practice.

We claim:

1. A semiconductor integrated circuit device comprising:

a semiconductor substrate on which an integrated circuit is formed, said integrated circuit including at least one current mode type logic circuit and a constant current circuit connected to said logic circuit for supplying a constant current thereto; and reference means disposed at the outside of said semiconductor substrate and connected to said constant current circuit for determining said constant current,

said logic circuit comprising at least one reference transistor having a base electrode to which a reference signal is applied, and at least one input transistor having a base electrode to which an input signal is applied, the emitter electrodes of said input and reference transistors being connected to said constant current circuit and the collector electrodes of said transistors being adapted to produce at least one logic signal in response to said input signal, said constant current circuit including a grounded collector type first transistor having a base electrode connected to said reference means, a second transistor having its collector electrode connected to the base electrode of said first transistor, and a third transistor having its collector electrode connected to said logic circuit, the base electrodes of said second and third transistors and the emitter electrodes of said second and third transistors

being connected to a terminal for receiving a power source voltage.

2. A semiconductor integrated circuit device according to claim 1, which further comprises a series circuit composed of a resistor and a diode connected between the collector electrode of said second transistor and said power source terminal.

3. A semiconductor integrated circuit device according to claim 1, which further comprises a differential amplifier circuit connected between said reference means and the base electrode of said first transistor.

4. A semiconductor integrated circuit device according to claim 1, which further comprises emitter resistors for connecting the emitter electrodes of said second and third transistors to said power source terminal and a common-base resistor for connecting the bases of said second and third transistors to said power source terminal.

5. A semiconductor integrated circuit device according to claim 4, which further comprises a series circuit composed of a resistor and a diode connected between the collector electrode of said second transistor and said power source terminal.

6. A semiconductor integrated circuit device according to claim 3, which further comprises emitter resistors for connecting the emitter electrodes of said second and third transistors to said power source terminal and a common-base resistor for connecting the base of said second and third transistors to said power source terminal.

7. A semiconductor integrated circuit device according to claim 1, which further comprises a pair of Schottky barrier diodes connected between the respective collectors of the transistors of said logic circuit and a source of reference potential.
